UNITED STATES PATENT OFFICE.

ERNEST L. TRIMBLE, OF PHILADELPHIA, PENNSYLVANIA.

WINDOW-SHADE PULL-CORD CLIP.

Application filed July 6, 1925. Serial No. 41,556.

My invention relates to clips for attaching pull cords to window shades.

Pull cords are ordinarily attached to the stick in the hem of a window shade by small screw eyes. This method of attaching the pull cord is objectionable because the lengthwise shifting of the stick in the hem moves the screw and mars the hem so that it imparts a worn and unneat appearance to the shade and the screw is unhandy to attach and is often pulled out of the stick when pulling the shade by the cord. Many clips were produced for attaching the pull cords but were unsatisfactory because they had teeth or other projections which pierced the hem and penetrated the stick to obtain a purchase. Due to the stick being loosely inserted in the hem, a slight shifting of the stick or a downward pull of the cord would cause the projections to cut or tear the hem at the parts where they passed into the stick.

The objects of my invention are to provide a clip which will firmly hold the pull cord to the hem and stick of a window shade without marring the hem or injuring the stick and which is free of teeth or projections.

These objects, and other advantageous ends which will be described hereinafter, I attain in the following manner, reference being had to the accompanying drawing in which

Figure 1 is a face view of a clip made in accordance with my invention illustrating it attached to a window shade and a pull cord, Figure 2 a section on line 2-2 of Figure 1,

Figure 3 a section on line 3-3 of Figure 1, illustrating the manner in which the clip is attached,

Figure 4 a vertical section through a modified form of the clip shown in Figure 2, and Figure 5 a section on line 5-5 of Figure 4.

Referring to the drawings, 1 indicates the hem of a shade, 2 the stick in the hem, 3 my improved clip and 4 the pull cord of a tassel or ring attached to the clip. The clip is stamped from a piece of spring metal and bent into a U-shape with the legs 5 of the U inclined toward each other and of less length than the depth of the hem. An opening 6 is punched in the bottom of the clip

through which cord 4 is passed and knotted inside of the clip. The side edges 7 of the clip are preferably chamfered to prevent cutting the hem when attached.

In Figures 4 and 5, I have shown a clip of modified form. It is similar in all respects to the clip shown in Figures 1-3, excepting the addition of resiliency to the clip by securing a pair of spring strips 8 within grooves 9 by rivets 10. I have given the corresponding parts of this clip the reference characters of the preferred form with the exponent a.

To attach the clip to the hem, the stick is removed and the clip is slipped over the hem. The stick is then passed through the hem and forced in between the inclined legs 5 of the clip to spring them apart from the dot-and-dash line position to the full line position shown in Figure 2. The end of the stick is preferably tapered as shown at 11 to facilitate its passage between the legs of the clip as shown in Figure 3.

The entire gripping faces of the clip bearing tightly against a large area of the hem, allows a clip of strong spring metal to be used without the danger of injuring the stick or marring the hem. A clip of strong spring metal will, when attached in this manner, be under such tension that the legs 5 of the U will firmly grip the hem and stick and hold the pull cord to the shade under severe use.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claim.

Having thus described my invention, what I claim as new and desire to secure by Letters Patent is:—

A clip of U-cross section provided with grooves in a leg of the U, and spring strips secured within the grooves.

In testimony whereof I have signed my name to this specification.

ERNEST L. TRIMBLE.
